Kathleen A. Costigan

(57) **CLAIM**

The ornamental design for a wallplate, as shown and described.

DESCRIPTION

FIG. 1 is a front perspective view of a first embodiment of a wallplate showing my new design.

FIG. 2 is a front view thereof;

FIG. 3 is a rear view thereof;

FIG. 4 is a left side view thereof, the right side view being a mirror image thereof;

FIG. 5 is a bottom view thereof, the top view being a mirror image thereof;

FIG. 6 is a front, perspective view of a second embodiment of a wallplate showing my new design.

FIG. 7 is a front view thereof;

FIG. 8 is a rear view thereof;

FIG. 9 is a left side view thereof, the right side view being a mirror image thereof; and

FIG. 10 is a bottom view thereof, the top view being a mirror image thereof.

FIG. 11 is a front, perspective view of a third embodiment of a wallplate showing my new design.

FIG. 12 is a front view thereof;

FIG. 13 is a rear view thereof;

FIG. 14 is a left side view thereof, the right side view being a mirror image thereof; and,

FIG. 15 is a bottom view thereof, the top view being a mirror image thereof.

The area shown in broken lines form no part of the claimed design.

1 Claim, 8 Drawing Sheets
